RAILWAY SIGNALING SYSTEM

Frank H. Richterkessing, Louisville, Ky., assignor
to Nachod & United States Signal Co., Incor-
porated, Louisville, Ky., a corporation of
Kentucky

Application June 25, 1937, Serial No. 150,237
Renewed November 22, 1939

18 Claims. (Cl. 246—128)

My invention relates to a system of signaling adapted to govern car or train movements on an electric or other railway, and more particularly to a railway having a single track section 5 equipped with a plurality of turnouts or sidings.

The principal application of my invention resides in the signaling of a main line haulage of a mine employing a single track railway connecting the various working sections of the mine by 10 a plurality of branch track sections.

My invention embraces a system of and apparatus for electric signaling, in which the signal control apparatus for each signal station of the signaled section is entirely symmetrical; the complete signaled section being made up of duplicate control apparatuses for each entry desired to be protected and operatively connected through two line wires.

My invention resides in a signaling system in 20 which any number of signal stations may be added to an existing signaled section by merely adding similar parts for each additional signal station without increasing the number of controlling line wires.

25 My invention also embraces a signaling system in which only one proceed signal is displayed under conditions of simultaneous entrance, regardless of the number of vehicles involved in the simultaneous movement.

30 My invention resides further in a signaling system which, once set into operation by a vehicle entering the signaled section, can not be changed by the entrance of other cars into the signaled section, until the vehicle for which the signaling protection was established passes out of the signaled section.

35 My invention resides further in the providing of a signaling system in which an "open" in either of the signal controlling line wires will effect a failure on the "safe side", that is, an open in the signal controlling line wire, which is often encountered in mines by the breaking of a line wire due to falling slate, roof cave-ins, etc., will automatically set all signals at red and prevent any further change in the display of the signals until such conditions are corrected. The opening of the restoring line wire will automatically set one or more of the signals at red, dependent upon the location of the break in the line wire, and similarly prevent restoration of the signals to normal until the fault is corrected.

40 My invention resides further in a signaling system that is primarily intended for use with those vehicles collecting propulsion current from a trolley wire by trolley wheels or shoes, and in which

the control of the signals is activated by trolley contactors engaged during the movement of the current collectors on the trolley wire.

45 My invention further resides in the locating of the trolley contactors at each signal station, such that separate locations are employed for the respective setting and restoring trolley contactors, thereby preventing the restoration of the signals to normal by a vehicle reversing its movement at the setting contactor location.

50 My invention still further resides in the arranging of the signal control circuits, such that the source of current for operating the controls governing the "proceed indication," is obtained from only one signal station hereinafter referred to as the "principal" signal station.

55 My invention further resides in the arrangement of the signal circuits, wherein, under conditions of simultaneous entrance of vehicles into the signaled section, the controls will definitely establish a proceed indication at the signal station nearest the "principal" station. The object of such an arrangement being to favor the movement of a vehicle operating with either a heavy load or requiring to climb a grade. Such favoring in the vehicle control of the signals may be utilized to other advantages, such as the elimination of rapid braking on steep grades, retarded main line movements, etc.

60 My invention further resides in the inclusion of a dispatcher control in the signal system without additional line wires, such control enabling a dispatcher to hold or set all signals at red and prevent a train from entering the signaled section, for such emergencies as cave-ins, track damages, broken trolley wire, derailed train, etc.

65 It will be further obvious to those skilled in the art that, by reason of the novelty and originality of my signal system, there are many other objects that will become apparent as the specification is read in connection with the accompanying drawing. For an illustration of one embodiment of my invention, reference is made to the accompanying drawing, in which—

70 Figure 1 is a diagrammatic representation of the circuits and apparatus illustrating one form of my invention.

75 Fig. 2 is a fragmentary diagrammatic illustration of a "directional" relay system that may be substituted for the mechanical trolley contactors S1 and N1 employed in Fig. 1.

80 Fig. 3 is a diagrammatic illustration of the circuits and apparatus of another form of directional control illustrated in Fig. 2.

85 Referring to Fig. 1, the conductor or trolley

wire T represents a "feeder" supplying operating current to both the signaling system and the vehicles operating on the section of the railway system, while, as is well understood in the art, 5 the return conductor for the current is either the earth y, track rails x or both as conditions may require.

As hereinbefore expressed, the major object of my invention is to provide a signaling system, for 10 a section of railway track consisting of a plurality of entries into a main track section, in which each entry constitutes a signal station and wherein any desired number of stations may be connected to form a unitarily controlled signal 15 section. Since three stations may be conveniently employed to illustrate the operation of such a signaling system, Fig. 1 diagrammatically illustrates such embodiment.

In Fig. 1 the section of railway extending between stations 1 and 3 may be regarded as the 20 main track section, and it is to be noted that one end of the main track section at station 3 is illustrated as comprising a passing siding, while the other end at station 1 is represented as forming 25 a continuation of the single track. It will be further noted that the above referred to main track section is joined by a single track turnout, which will be hereinafter identified as signal station 2.

30 Although the accompanying drawing illustrates my invention as applied to an electric railway, wherein the signal controlling apparatus is actuated by a suitable form of "trolley contactor," I do not desire to limit my invention to this particular application, since the principles embodied in my invention are readily applicable to signaling systems in which the control may be responsive to the operation of photo electric devices, magnetic inductors, track instruments, track circuits, 40 or any other form of control that will retain the relay system active as long as a vehicle occupies the section of railway between the various signal stations.

In the embodiment of my invention, illustrated 45 in Fig. 1, each signal station is provided with vehicle controlled contact mechanisms whereby a member, such as a traveling contact or trolley wheel carried by a moving car or train, causes closure of signal control circuits. These vehicle controlled contact mechanisms may comprise suitable mechanically movable contact members, indicated at station 1 as N1 and S1 respectively, that are deflectable in opposite directions by the trolley wheel or some other member carried by 50 the car or train, according to the direction of travel of the car or train.

At signal station 1 the movable contact member N1 is provided with a stationary contact 33, which, as indicated by the arrow, is engaged by 60 the contact member N1 only when the car leaves the signaled section. It will be further noted that the movable contact member S1 is provided with a stationary contact 1, which, as indicated by the direction of the arrow adjacent member S1, is engaged by the member S1 only when a train is 65 entering the signaled section.

While this simple mechanical type of directional sensitive vehicle controlled mechanism is described, it is to be understood that any other 70 suitable directional-sensitive circuit controlling mechanism may be employed. Such circuit controlling mechanisms are in part diagrammatically illustrated in Figs. 2 and 3, which will be herein-after described in detail.

75 The signal indications of the system are dia-

grammatically illustrated as signal lamps. However, it is to be understood that any suitable form of signaling means may be substituted for such signal lamps.

The signal lamps are adapted to convey to the 5 operator of a vehicle the condition of the signaled territory, that is, whether same is occupied by train movements, and the direction in which such movements are being made. It is to be further understood that these signal lamps 10 are provided with suitable colored roundels to distinguish the indications. In the embodiment illustrated, I have employed red roundels for lamps R1, R2 and R3 to denote Stop, and green roundels for lamps G1, G2 and G3 to indicate Proceed. A similar red roundel is provided for signal lamp R.

In Fig. 1 similar relays are employed at each signal station. At station 1 these relays are, namely; a neutral relay M1 and a mechanical 20 interlocking relay C1—A1. It will be well to note that the similar relays at each signal station together with all other similar apparatuses are designated by similar characters. For instance, the neutral relay in station 1 is designated as M1, 25 while the neutral relay in station 3 is designated as M3, etc.

The operation of the mechanical interlocking relay A1—C1 is very simple. The relay consists of two neutral relays positioned side by side with 30 a mechanical latch member XI arranged to be engaged by the armatures of the respective neutral relays. When the armature B1 of relay C1 is attracted, the latch member XI is moved out of the path of the armature D1 of the neutral 35 relay A1, thereby permitting the armature D1 of relay A1 to remain in its unattracted position so long as the operating coil of relay A1 remains de-energized. When the operating coil of relay C1 is de-energized and its armature B1 releases, 40 the mechanical latch XI will move into the path of armature D1 of relay A1. It will be evident, therefore, that when the operating coil of relay A1 is momentarily energized, the armature D1 of relay A1 will be mechanically locked in its 45 actuated condition regardless of the condition of the operating coil of relay A1 after such operation. Also, when the armature B1 of relay C1 is subsequently attracted to its operated position, the latch XI will be moved out of the path 50 of armature D1, thereby permitting the armature D1 to restore to its normal condition.

Before proceeding with the detailed description of the operation of Fig. 1, it is believed that notation should be made of the normal condition 55 of the relays and signals in my system. Normally, with no trains occupying the signaled section, all signals are held at dark, and neutral relays M1, M2 and M3 are retained de-energized. Similarly, the operating coils of relays A1, A2 and 60 A3 are de-energized. However, it is well to note that the operating coils of relays C1, C2 and C3 are normally energized holding their respective armatures normally in an actuated condition. Observing the circuits of station 1, it will be 65 noted that the armature B1 normally engages its front contact 4 and disengages its back contact 11, thereby normally connecting the operating coil of relay A1 to the earth or negative return of the current supply, and opening the circuit of the 70 signal lamps G1 and R1. Thus as long as the operating coils of the C relays of each signal station are retained energized, the signals are held dark and the operating coils of the A relay are held in condition to be energized in response to 75

Vehicle operation of Figure 1

the entrance of a vehicle into the signaled section. However, when the operating coils of the C relays are de-energized, the operating coils of the A relays are withheld from energization, and a circuit is completed at each signal station to one or other of the respective signal lamps, dependent upon the selection determined by the respective M relay. From the foregoing it will be obvious that regardless of the manner in which the operating coils of the C relays are de-energized, whether due to an open coil, a short circuited coil, faulty ground connection, broken line wire, etc., the operating magnets of the A relays will be "locked out," that is, withheld from operation, and the local circuit to the signal lamps at each station completed.

Two line wires interconnect the signal stations of the complete signaled section. Line wires 20 and 29 interconnect stations 1 and 2 while line wires 22-22a and 26 interconnect stations 2 and 3. If it is desired to have another station located between stations 1 and 2 no additional line wiring would be required. The extra station would merely connect to the existing line wires 20 and 29. Similarly any number of stations could be added between stations 2 and 3 for instance by merely connecting to the existing line wires 22-22a and 26. If it is desired to include a signal station remote from the section presently signaled, it would be necessary to run two line wires to the nearest point of the signaled section.

The dispatcher control of Fig. 1 consists of a normally closed switch inserted in the signal controlling line wire 20 or 22-22a. Any number of these switches may be inserted in either of these line wires at points convenient to the dispatcher. These switches may be of any desired construction but preferably a rotary snap switch of the indicating type. The character D illustrates such a snap switch installed in the signal line wire 22-22a. At times it is desirable to cause the stop signal at one station to be continuously active to prevent trains entering the signaled section at this point. This independent control of the signal is accomplished by opening the circuit of the operating coil of the C relay at the station where the stop signal is to display. If it is desired to cause the stop signal R1 at station 1 to be continuously illuminated, wire 21 is disconnected thereby opening the circuit of the operating coil of relay C1. This de-energization of the operating coil of relay C1 will cause armature B1 to open the circuit of the operating coil of relay A1, and complete the circuit of signal R1. Similarly wires 61 or 25 of stations 2 and 3 may be disconnected. It is to be noted that this control of the signal at station 1 in no way affects the operation of the signals at stations 2 and 3. Car or train operations at stations 2 and 3 may continue in a normal manner unaware of the condition of station 1. In this way if congestion has occurred on any one of the routes the signals may be controlled by opening the circuit of the operating coil of the respective C relay, and permit uninterrupted movement of the cars or trains between the other stations. It is likewise important to note that when the dispatcher switch D is opened, all signals will simultaneously display their stop indication, which condition can not be changed by either the entrance of a car into the signaled section or by a car leaving the signaled section. The signals will therefore continue to display their restricted indication until the dispatcher switch is restored to its normal condition.

With no car or train in the signaled section, all signals are held in a normal-dark condition. The control effecting this condition of the signals is the circuit normally retaining the C relays energized. In Fig. 1 this circuit is established from the positive conductor T at station 1, through wire 6, armature D1 of relay A1, contact 19, line wire 20, armature D2 of relay A2 at station 2, contact 21, line wire 22, snap switch D, wire 22a, armature D3 of relay A3 at station 3, contact 23, jumper wire 24, wire 25, operating coil of relay C3, through wire 10 to the ground return. It will be further noted that the operating coil of relay C1 is likewise connected to receive positive potential from jumper wire 24, through wires 26 and 27; the operating coil of relay C1 being connected to the ground return through wire 28. Similarly, the operating coil of relay C2 is connected to receive positive potential from jumper wire 24 through wires 26, 29 and 61; the operating coil of relay C2 being connected to the ground return through wire 30. The latter mentioned circuit from jumper wire 24 merely establishes a flow of energization current from the signal line wire 20-22-22a, which includes an armature and back contact of the respective A relays at each signal station, through the jumper 24 to the restoring line wire 26-29 which normally connects the operating coils of the respective C relays of each signal station in a multiple circuit. This circuit for retaining the operating coils of the C relays normally energized may be regarded as a stick or retaining circuit. With further reference to Fig. 1 it will be noted that the restoring line wire 26-29 is connected to receive an initial energizing impulse from one of the restoring contactors N. At station 1 it will be noted that the restoring contactor N1 connects the restoring line wire 26-29 through contact 33. At station 2 the restoring contactor N2 connects the restoring line wire 29-26 through wire 31 and contact 32. At station 3 the restoring contactor N3 is connected to the restoring line wire 26-29 through contact 34. It will be apparent that an operation of either of the N restoring contactors will momentarily connect the operating coil of each respective C relay to the positive conductor T. This operation of the C relays will condition the signal circuits so that the retaining circuit will be immediately established from wire 6 at station 1, through the signal line wire 20-22-22a, and jumper wire 24.

Assuming that a vehicle is entering at station 1, the engagement of its trolley wheel with the restoring contactor N1 will have no effect on the operation of the system. However, when the trolley wheel of the entering vehicle engages the setting contactor S1, a circuit is completed from the positive conductor T through member S1, contact 1, wire 2, operating coil of relay A1, wire 3, contact 4, armature B1 of relay C1, wire 5 to the ground return. This energization of the operating coil of relay A1 will cause the armature D1 of relay A1 to disengage its back contact 19 and to be brought into engagement with its front contact 7. This disengagement of back contact 19 removes jumper wire 24 from positive potential, thereby de-energizing the operating coils of the C relays at each respective signal station, and causing their respective armatures to release from their operated condition. When armature B1 of relay C1 releases, the operating circuit of relay A1 is opened by the disengagement of contact 4, and

simultaneously the mechanical latch X_1 moves into the path of armature D_1 to mechanically retain the armature D_1 in its operated position. Similarly, armature B_2 of relay C_2 releasing, disengages its front contact and thereby opens the operating circuit of the coil of relay A_2 . Likewise, armature B_3 of relay C_3 releasing, disengages its front contact and thereby opens the circuit of the operating coil of relay A_3 . The releasing of armatures B_2 and B_3 permits mechanical latches X_2 and X_3 to move into the path of the armatures of the A relays at stations 2 and 3. However, since these armatures are in their normal unoperated positions, no further effect will be apparent at these signal stations.

Instant to the operation of armature D_1 , a circuit is established for the energization of the operating coil of relay M_1 , this circuit being completed from the positive conductor T , through wire 6, armature D_1 , front contact 7, wire 8, operating coil of relay M_1 , wire 9 to the ground return. This energization of the operating coil of relay M_1 will cause the armature H_1 to disengage its back contact 13 and come into engagement with its front contact 15.

The release of armature B_1 at station 1 also completed a circuit for energizing the proceed signal G_1 . This circuit being completed from the positive conductor T , through wire 18, signal lamp G_1 , wire 16, contact 15, armature H_1 , wire 12, contact 11, armature B_1 , wire 5 to the ground return. The release of armature B_2 at station 2 completed a circuit for energizing stop signal R_2 . The latter circuit being completed from the positive conductor T , through wire 18a, wire 17a, signal lamp R_2 , wire 14a, contact 13a, armature H_2 , wire 12a, contact 11a, armature B_2 , wire 5a to the ground return. The release of the armature B_3 at station 3 similarly completed a circuit for energizing the stop signal R_3 .

In the preceding description it was assumed that a single car entered at station 1. To explain the operation of my system under simultaneous operation it will be assumed that a car enters at station 2 simultaneously with the car at station 1. Under this condition of operation, the operating coil of relays A_1 and A_2 will be simultaneously energized. The operation of armatures D_1 and D_2 will remove the signal clearing control wire 28-29 from positive potential, and thereby cause the operating coils of relays C_1 , C_2 and C_3 to become de-energized. Inasmuch as armatures D_1 and D_2 were simultaneously operated, the de-energization of the operating coils of relays C_1 and C_2 will permit the mechanical latches X_1 and X_2 to move into the path of the armatures D_1 and D_2 and retain them in their operated positions. Referring particularly to the circuits of station 1, it will be noted that the operation of armature D_1 removed positive potential from armature D_2 of station 2. Therefore, the operating coil of relay M_1 , at station 1, will be energized via armature D_1 and contact 7, which will permit the energization of the proceed signal G_1 . At station 2, the operating coil of relay M_2 can not be energized, therefore, the stop signal R_2 will be energized in the same manner as described in connection with a single car entering at station 1. Similarly, stop signal R_3 at station 3 will be energized. Thus with cars entering simultaneously at stations 1 and 2, only the car approaching station 1 will receive a proceed signal.

I will now assume that the car at station 2 operated the setting contactor S_2 slightly before

the car at station 1 operated its setting contactor S_1 . With this condition of operation it will be apparent that the operating coil of relay A_2 will be energized before the operating coil of relay A_1 . It will also be apparent that, if this time is sufficient to permit the armature B_1 to disengage contact 4 before the operating coil of relay A_1 can operate its armature D_1 , the mechanical latch X_2 will retain armature D_2 operated while armature D_1 will remain in its unoperated position. Thus, the armature D_2 being connected to positive potential T via wire 20, contact 19, armature D_1 and wire 6, will bring about the energization of the operating coil of relay M_2 . Therefore, the armature H_2 will disengage contact 13a and energize proceed signal G_2 through its front contact. At station 1, however, since the armature D_1 was not operated, the operating coil of relay M_1 will not be energized. Therefore, the release of armature B_1 will energize the stop signal R_1 through the circuit completed from the positive conductor T , wire 18, wire 17, stop signal R_1 , wire 14, contact 13, armature H_1 , wire 12, contact 11, armature B_1 , wire 5 to the ground return. Inasmuch as no car operated at station 3, the stop signal R_3 will be displayed as hereinbefore mentioned.

From the foregoing it will be apparent that in order for the proceed signal to be displayed at a station remote from the principal station where the signal control wire is connected to positive potential, it will be necessary for the armature of the respective A relay to be operated before the armature of an A relay nearer the principal station. Thus, according to Fig. 1 under simultaneous operation of armatures D_1 , D_2 and D_3 , station 1 will receive the proceed signal. Under simultaneous operation of armatures D_2 and D_3 , station 2 will receive the proceed signal. However, under any circumstances if, for instance, armature D_3 is operated before armature D_1 or D_2 , the operating coil of relay M_3 will be energized to permit the proceed signal G_3 to be displayed at station 3. Thus, the signaling is absolute in its control, and will permit but one car to occupy the signaled section at a time.

When the car receiving the proceed signal advances and leaves the block, a restoring contactor N will be operated to restore the signals and relays to normal. For the purpose of illustration it will be assumed that a car operating at station 1 has received the proceed signal G_1 and leaves the signaled territory at station 3. When the restoring contactor N_3 is operated, contact 34 will be connected to positive potential, and the operating coils of relay C_1 , C_2 and C_3 energized. This will result in armatures B_1 , B_2 and B_3 being restored to their normal operated positions. Thus the mechanical latches X_1 , X_2 and X_3 will be moved out of the path of armatures D_1 , D_2 and D_3 , which will re-establish the retaining circuit for the operating coils of relays C_1 , C_2 and C_3 . The latter circuit being completed from positive conductor T at station 1, through wire 6, armature D_1 , contact 19, wire 20, armature D_2 , contact 21, wire 22, switch D , wire 22a, armature D_3 , wire 24, wire 25, operating coil of relay C_3 , through wire 10 to ground. Wire 26 being connected to wire 24 will likewise energize the operating coil of relay C_1 via wires 27 and 28. Similarly since wire 29 connects wire 26, the operating coil of relay C_2 will be energized via wires 61 and 30. It is to be noted that the operating coils of relays C_1 , C_2 and C_3

are arranged in a multiple circuit. Therefore, regardless of whether the restoring contactor N1, N2 or N3 is operated, the coils and signals will be restored to normal in the same manner.

- 5 At station 2 a stop signal R is provided and located to stop a car approaching station 2 before operating the setting or restoring contactors, whenever the signaled section is occupied. Referring to the circuits of station 2, it will be noted 10 that whenever the armature B2 of relay C2 is released, the stop signal R is displayed. The circuit for stop signal R being completed from positive conductor T, through wire 36, stop signal R, wire 35, contact 11a, armature B2, wire 15 5a to ground return. The purpose of stop signal R is to prevent cars approaching the signaled section from passing its respective setting contactor while the signaled section is occupied, and it is to be understood that a similar stop signal 20 is to be provided at stations 1 and 3 when this feature is required.

In Figs. 2 and 3 a direction-sensitive relay system is illustrated that may be substituted for the mechanical type of contactors shown in Fig. 1. Referring particularly to Fig. 2, it will be observed that two contact strips 37 and 38 are arranged adjacent the positive conductor T so that a trolley wheel W moving in the direction of the arrow will first connect the contact strip 37 to the positive conductor T, then contact strip 38. Such a relay system is described in the United States Patent to Frank H. Richterkessing et al. 1,915,696, issued June 27, 1933. In Fig. 2 it is proposed to connect wire 41, for instance, to wire 2. Thus, the trolley wheel W moving in the direction of the arrow consecutively energizing the coils of relays E and F will bring the armature L into engagement with contact 46 thereby completing a circuit for energizing the operating coil of relay A1 from the positive conductor T, through the current collector W, contact strip 38, wire 44, wire 45, contact 46, armature L, wire 47, wire 2, operating coil of relay A1, wire 3, contact 4, armature D1, wire 5 to the ground return.

In Fig. 3 a similar relay system is illustrated. However, this system does not require the consecutive energization of the operating coils of relays E1 and F1, but on the other hand selective energization of same, dependent upon the consecutive engagement of the contact member 48 and 49. For illustration, assuming that the current collector W travels in the direction of the arrow, the contact strip 48 is first connected to the positive conductor T, thereby completing a circuit for energizing the operating coil of relay F1 via wire 58, armature K3, contact 51, wire 53, operating coil F1, wire 54 to ground G. When the trolley wheel W subsequently engages the contact strip 49 a circuit will be completed for retaining the operating coil of relay F1 energized via wire 55, armature L3, front contact 60, operating coil of relay F1, wire 54 to ground G. When the trolley wheel moves in the direction reverse to that indicated by the arrow, the contact strip 49 will be first connected to the positive conductor T, thereby energizing the operating coil of relay E1 via wire 55, armature L3, contact 56, wire 57, operating coil of relay E1, wire 58, ground G. Thus when the contact strip 48 is subsequently engaged the operating coil of relay E1 will be retained energized via wire 50, armature K3, contact 59, etc. In order to employ such a relay system in connection with Fig. 1, it is proposed that wire 52 of Fig. 3 be connected

to wire 2 of Fig. 1. Thus, whenever the operating coil of relay F1 is energized via contact 51, the wire 52 will connect the operating coil of relay A1 to the positive conductor T. Having thus described my invention—

I claim:

1. A block signaling system having a plurality of signal stations, and having two control wires, each extending between at least two stations, the combination therewith including, a source of power at one station; normally closed switch means at the said one station connecting one terminal of the said source of power to one of said control wires; normally closed switch means at the other of said stations connecting the said one control wire to the other control wire; a relay at each of the said stations, each relay having a winding normally energized in a circuit including the said switches and said control wires; control means at each of the said stations operable to actuate the corresponding switch means so as to open the said circuit including the said control wires, and to thereby de-energize the windings of the said relays; means at each of the said stations, operated by the corresponding relay, for retaining the corresponding switch means actuated, when the winding of the corresponding relay is de-energized; a second relay at each of the said stations each second relay having a winding normally de-energized and adapted to be connected to the source of power for energization, when the corresponding switch means is actuated; a proceed signal at each of the said stations; means, controlled by the de-energization of the winding of a first mentioned relay and the energization of the winding of a corresponding second mentioned relay, to operate the corresponding proceed signal; a stop signal at each of the said stations; and means, controlled by the de-energization of the winding of the first mentioned relay and the de-energization of the winding of the corresponding second mentioned relay, to operate the corresponding stop signal.

2. A block signaling system having a plurality of signal stations, and having two control wires extending between at least two stations, the combination therewith including, a source of power at one station, normally closed switch means at the said one station connecting one of said control wires to one terminal of the said source of power; normally closed switch means at the other of said stations connecting the said one control wire to the other control wire; a relay at each of the said stations, each relay having a winding normally energized in a circuit including the said switches and said control wires; control means at each of the said stations, operable while the corresponding winding is energized, to open the corresponding switch means to deenergize the said windings; means at each of the said stations, operated by the de-energization of the corresponding winding, to retain the corresponding switch means open; signaling means at each of the said stations; and means at each of the said stations, operated by the de-energization of the corresponding winding, to operate the corresponding signaling means.

3. A block signaling system having a plurality of signal stations, and having two control wires extending between at least two stations, the combination therewith including a source of power at one station; normally closed switch means at the said one station connecting one of the control wires to one terminal of the source of power; normally closed switch means at the other of

said stations connecting the said one control wire to the other control wire; a relay at each of the said stations, each relay having a winding normally energized in a circuit including the said switches and the said control wires; control means at each of the said stations, operable while the corresponding winding is energized, to actuate the corresponding normally closed switch so as to open the said circuit including the said control wires, and to thereby de-energize the said windings; means at each of the said stations, operating when the corresponding winding is de-energized, to retain the corresponding switch actuated; a second relay at each station, each 15 second relay having a winding normally de-energized and adapted to be connected to the source of power for energization when the corresponding switch means is actuated; means, controlled by the simultaneous actuation of the said switches, providing energization of only one of the windings of the said second relays; stop and proceed signals at each station; means, operated by the de-energization of the winding of a first mentioned relay and the energization of the 20 winding of the corresponding second mentioned relay, to operate the corresponding proceed signal; and means, operated by the de-energization of the winding of the other first mentioned relay, to operate the corresponding stop signal.

30 4. A block signaling system having a plurality of signal stations and having two control wires, each extending between at least two stations, the combination therewith including, a source of power at one station; normally closed switch means at the said one station connecting one terminal of the said source of power to one of the said control wires; normally closed switch means at the other of said stations connecting the said one control wire to the other control 35 wire; a relay at each of the said stations, each relay having a winding normally energized in a circuit including the said switches and said control wires; control means at each station, operable while the corresponding winding is energized, to actuate the corresponding normally closed switch so as to open the said circuit including the said control wires, and to thereby de-energize the said windings; means at each of the said stations, operating when the winding of the corresponding relay is de-energized, for retaining the corresponding switch actuated; a second relay at each of the said stations, each second relay having a winding normally de-energized and adapted to be connected to the source of power for energization 40 when the corresponding switch means is actuated; means, controlled by the simultaneous actuation of the said switches, providing energization of only one of the windings of the said second mentioned relays; a proceed signal at each station; means controlled by the de-energization of the winding of a first mentioned relay and the energization of the corresponding second mentioned relay, to operate the corresponding proceed signal; a stop signal at each station; and means, controlled by the de-energization of the windings of the corresponding first and second mentioned relays, to energize the corresponding stop signal.

45 5. A block signaling system having a plurality of signal stations and having two control wires each extending between at least two stations, the combination therewith including, a source of power at one station; normally closed switch means at the said one station connecting one of the said control wires to one terminal of the

said source of power; normally closed switch means at the other of said stations connecting the said one control wire to the other control wire; a relay at each of the said stations, each relay having a winding normally energized in a circuit including the said switches and the said control wires; control means at each of the said stations, operable while the corresponding winding is energized, to actuate the corresponding normally closed switch so as to open the said circuit including the said control wires, and to thereby de-energize the said windings; means at each of the said stations, operating when the corresponding winding is de-energized, to retain the corresponding switch actuated; signaling means at each station operated by the corresponding relay, when the winding of the corresponding relay is de-energized; and means operable to re-energize the winding of each of the said relays, to discontinue operation of the signaling means, as recited.

6. A block signaling system having a plurality of signal stations, the apparatus at one of said stations comprising, a normally open circuit including a first electromagnet; means responsive to the entry of a car into the block at the said one station, for closing the said circuit so as to energize the said first electro-magnet; an armature operated by the said first electro-magnet; a second electro-magnet and an armature operated thereby; a mechanical latch associated with the armature of the first electro-magnet, and operated by the armature of the said second electro-magnet, for retaining the armature of the said first electro-magnet in its operated position; a third electro-magnet and an armature operated thereby; means including contacts of the armature operated by the first electro-magnet in its energized condition, for energizing the said third electro-magnet; a proceed signal; and means including contacts of the armature operated by the third electro-magnet in its energized condition and contacts of the armature operated by the second electro-magnet in its de-energized condition, for operating the said proceed signal.

7. A block signaling system having a plurality of signal stations (1, 2 and 3), and having two control line wires (wires 20—22—22a; and wire 26), each extending between at least two stations (1 and 3) the combination therewith including, a source of power (T—X) at one station (station 1); one of said control line wires (20, etc.) being connected (via wire 6) to one terminal (T) of the said source of power at the said one station (station 1), and connected (via jumper wire 24) to the other control line wire (26) at another of said stations (station 3); a relay at each station (C1 and C3), each relay having a winding normally energized and connected between the said other control line wire (26) and the other terminal (X) of the said source of power; control means (D1 and D3) at each station, each control means operable to open the said one control line wire (26, etc.), and to thereby de-energize the winding of each relay (C1 and C3); means (X1 and X3) at each station, each means operated by the corresponding relay (C1 and C3), to retain the corresponding control means (D1 and D3) operated, when the winding of the corresponding relay (C1 and C3) is de-energized; a second relay (M1 and M3) at each station, each second relay having a winding normally de-energized and adapted to be connected to the said source of power (M1 via D1—7 and 9) 75

ature (D1) for the first electro-magnet (A1); means (S1), responsive to the entry of a car into the block at the said one station, for closing the said circuit so as to energize the said first electro-magnet, and thereby operate the said armature (D1) of the first electro-magnet; a second electro-magnet (C1) normally energized; an armature (B1) for the said electro-magnet normally retained in its operated condition by the second 5 electro-magnet; means (X1) for retaining the said armature (D1) of the first electro-magnet in its operated condition, the said retaining means (X1) being controlled by the said armature (B1) of the said second electro-magnet (C1); and 10 means (D1-19), responsive to the operation of the said armature (D1) of the said first electro-magnet, for de-energizing the said second electro-magnet (C1), and thereby operate the said retaining means (X1) so as to retain the said 15 armature (D1) of the first electro-magnet in its operated condition; a proceed signal (G1); and means, responsive to the operated condition of the said armature (D1) of the first electro-magnet, cooperating with means (B1-11) responsive 20 to the non-operated condition of the said armature (B1) of the second electro-magnet, for operating the said proceed signal (G1).

12. A block signaling system having a plurality of signal stations (1, 2 and 3), the apparatus at 30 one of said stations (station 1) comprising, a normally open circuit (comprising wires 2, 3 and 5) including a first electro-magnet (A1); an armature (D1) for the first electro-magnet (A1); means (S1) responsive to the entry of a car into the block at the said one station, for closing the said circuit so as to energize the said first electro-magnet, and thereby operate the said armature (D1) of the first electro-magnet; a second electro-magnet (C1) normally energized; 35 an armature (B1) for the said electro-magnet normally retained in its operated condition by the second electro-magnet; means (X1) for retaining the said armature (D1) of the first electro-magnet in its operated condition, the said retaining means (X1) being controlled by the said armature (B1) of the said second electro-magnet (C1); and means (D1-19), responsive to the operation of the said armature (D1) of the said first electro-magnet, for de-energizing 40 the said second electro-magnet (C1), and thereby operate the said retaining means (X1) so as to retain the said armature (D1) of the first electro-magnet in its operated condition; a proceed signal (G1); and means, responsive to the operated condition of the said armature (D1) of the first electro-magnet, cooperating with means (B1-11) responsive to the non-operated condition of the said armature (B1) of the second electro-magnet, for operating the said proceed signal (G1); and means, (N1) responsive to the car leaving the block at the said one station, for re-energizing the said second electro-magnet (C1), and to thereby release the retaining means (X1) and restore the said armature (D1) of the 45 said first electro-magnet to its non-operated condition.

13. A block signaling system having a plurality of signal stations having similar apparatus, the apparatus at one station comprising, a normally open circuit including a first electro-magnet; an armature for the first electro-magnet; means responsive to the entry of a car into the block at the said one station, for closing the said circuit so as to energize the first electro-magnet, and thereby operate the said armature 50

ture of the first electro-magnet; a second electro-magnet normally energized; an armature for the said second electro-magnet normally retained in its operated condition by the said second electro-magnet; a mechanical latch, controlled by the armature of the said second electro-magnet, for retaining the armature of the first mentioned electro-magnet in its operated condition, when the said second electro-magnet is de-energized; a third electro-magnet normally de-energized; 5 an armature for the said third electro-magnet normally in a non-operated condition; stop and proceed signals controlled by the armature of the third electro-magnet; means responsive to the operation of the armature of the said first 10 electro-magnet, for de-energizing the said second electro-magnet, and thereby release the armature of the said second electro-magnet to operate latch so as to retain the armature of the first electro-magnet in its operated condition; 15 means, responsive to the operated condition of the armature of the first electro-magnet, for energizing the said third electro-magnet and to thereby operate the armature of the third electro-magnet; means, responsive to the releasing 20 of the armature of the second electro-magnet, cooperating with means responsive to the operation of the armature of the third electro-magnet, for operating the said proceed signal; and means, responsive to the non-operated condition of the 25 armature of the said third electro-magnet, cooperating with the said means responsive to the releasing of the armature of the second electro-magnet for operating the said stop signal.

14. A railway block signaling system for a 30 plurality of separated stations having, in combination, a source of power; a normally-energized relay at each station, each relay having a normally-energized relay-coil; a normally-closed line-circuit including the relay-coil at each station and the source of power for retaining the relay-coil at each station normally-energized; a normally-closed switch at each station, each switch included in the said circuit including all of the said relay-coils and operable to open the 35 said circuit for de-energizing all of the said relay-coils; control means at each station for operating the corresponding switch to open the said circuit; means at each station, operated by the de-energization of the corresponding relay-coil, for retaining the corresponding switch means 40 open; signaling means at each station; and means at each station, operated by the de-energization 45 of the corresponding relay-coil, for operating the corresponding signaling means.

15. A railway block signaling system for a plurality of separated stations having, in combination, a source of power; a first line connection extending to each station; a normally-energized electro-magnet at each station, each magnet 50 having one terminal connected to the first line connection and its other terminal connected to one terminal of the source of power; a normally closed switch at each station; a second line connection connecting the said first line connection to the other terminal of the source of power, the said second line connection including the normally closed switch at each station connected in series therewith; control means at each station operable to open the corresponding normally closed switch, for disconnecting the first line connection from the said other terminal of the source of power, and thereby to de-energize the electro-magnet at each station; means at each station, 55 operating in response to the de-energization of 60 the electro-magnet.

the corresponding electro-magnet, for retaining the corresponding switch means open; signaling means at each station; and means at each station, operating in response to the de-energization 5 of the corresponding electro-magnet, for displaying the corresponding signaling means.

16. A railway block signaling system for a plurality of separated stations having, in combination, a source of power; a first line connection extending to each station; a normally-energized electro-magnet at each station, each magnet having one terminal connected to the first line connection and its other terminal connected to one terminal of the source of power; a 10 normally closed switch at each station; a second line connection connecting the said first line connection to the other terminal of the source of power, the said second line connection including the normally closed switch at each station 15 connected in series therewith; control means at each station operable to open the corresponding normally closed switch, for disconnecting the first line connection from the said other terminal of the source of power, and thereby to 20 de-energize the electro-magnet at each station; means at each station, operating in response to the de-energization of the corresponding electro-magnet, for retaining the corresponding switch means open; a normally-open switch at 25 each station, closed by the operation of the corresponding control means; a proceed signal at each station; means at each station, controlled by the closing of the corresponding normally-open switch, for displaying the corresponding proceed signal; and means controlled by the opening of the said normally-closed switches providing for the display of only one of the said proceed signals, when more than one of the said normally-open switches are closed.

17. A railway block signaling system for a plurality of separated stations having, in combination, a source of power; a first line connection extending to each station; a normally-energized electro-magnet at each station, each magnet having one terminal connected to the first line connection and its other terminal connected to one terminal of the source of power; a normally closed switch at each station; a second line connection connecting the said first line connection to the other terminal of the source of power, the said second line connection includ-

ing the normally closed switch at each station connected in series therewith; control means at each station operable to open the corresponding normally closed switch, for disconnecting the first line connection from the said other terminal 5 of the source of power, and thereby to de-energize the electro-magnet at each station; means at each station, operating in response to the de-energization of the corresponding electro-magnet, for retaining the corresponding switch means 10 open; a stop signal at each station; means at each station operating in response to the de-energization of the corresponding electro-magnet, for displaying the corresponding stop signal; a proceed signal at each station; a normally-open 15 switch at each station, closed by the operation of the corresponding control means; means at each station, controlled by the closing of the corresponding normally-open switch, for displaying the corresponding proceed signal; and means controlled by the opening of the said normally-closed switches providing for the display of only one of the said proceed signals, when more than 20 one of the said normally-open switches are closed.

18. A railway block signaling system for a plurality of separated stations, having in combination, a source of power; signaling means at each of said stations; a control relay at each station; means at each station, controlled by the corresponding control relay, for operating 30 the corresponding signal; a normally-closed switch at each station; a first line connection extending to each station; a normally-energized operating-coil for each control relay, each coil 35 having one terminal connected to the said first line connection and its other terminal connected to one terminal of the said source of power; a second line connection connecting the said first line connection to the other terminal of the said source of power, the said second line connection 40 including the normally-closed switch at each station connected in series therewith; control means at each station operable to open the corresponding normally-closed switch, for opening the said second line connection, and thereby de-energize each of the operating coils of the said 45 control relays; and means at each station, operating in response to the de-energization of the corresponding relay coil, for retaining the corresponding normally closed switch opened. 50

FRANK H. RICHTERKESSING.
